UNITED STATES PATENT OFFICE.

JAMES A. BROGAN, OF LAWRENCE, MASSACHUSETTS, ASSIGNOR TO UNITED SHOE MACHINERY CORPORATION, OF PATERSON, NEW JERSEY, A CORPORATION OF NEW JERSEY.

REEL.

Original application filed April 27, 1918, Serial No. 231,205. Divided and this application filed August 18, 1921. Serial No. 493,321.

To all whom it may concern:

Be it known that I, JAMES A. BROGAN, a citizen of the United States, residing at Lawrence, in the county of Essex and State 5 of Massachusetts, have invented certain Improvements in Reels, of which the following description, in connection with the accompanying drawings, is a specification, like reference characters on the drawings indicating like parts in the several figures.

This invention relates to winding and reeling apparatus and is illustrated as embodied in a reel which is adapted for use in winding strips of welting or other stock in 15 hanks or skeins. In so far as there is common subject-matter the present application is a division of my prior application Serial No. 231,205, filed April 27, 1918, upon which United States Letters Patent No. 1,412,837 20 was granted April 18, 1922.

Strips of welting, such as are wound into hanks by machines of the type illustrated in my said prior application, are relatively short as compared to the lengths of yarn, 25 thread, etc., which are handled by ordinary winding and reeling machines, and it is accordingly much more important that a welt-winding machine be arranged to require as little time as possible in removing 30 one hank of welting and starting the operation of the machine in forming the next hank.

An object of this invention, accordingly, is to facilitate the removal of finished hanks 35 of welting or other stock, and the arrangement of succeeding strips for the operation of such a machine, as is hereinafter set forth.

One feature of the invention is to be found in the use of reel-arms which may be moved 40 from a winding to a releasing position, and which are simultaneously operative to decrease the effective diameter of the reel, thereby facilitating removal of a completed hank. As illustrated, each arm is eccentrically mounted to turn on a support, with a projecting end which extends outwardly to receive the strip of welting when the large side of the eccentric is turned outward to give a maximum effective reeling diameter, and 45 which extends inward out of the way when the arm is turned to decrease the effective reeling diameter to facilitate removal of the completed hank of welting.

Another feature of the invention com-

prises a clamp for the end of a succeeding strip, which is actuated by moving the reel arm back to winding position. In the present embodiment of the invention an abutment is provided to co-operate with the base of the reel arm as it is turned about on the support.

These and other features of the invention, including specific constructions and combinations of parts, will be apparent from the following description of an illustrative embodiment of my invention shown in the accompanying drawings, in which—

Fig. 1 is in part a cross-section and in part a side elevation of so much of my improved winding machine as shows the novel reel;

Fig. 2 is a view of one of the reel arms generally similar to a portion of Fig. 1, but showing the manner of operating the arm; and

Fig. 3 is a view similar to Fig. 2 showing a modified construction.

As explained in the above-identified prior application, my improved winding machine comprises generally a vertically-reciprocated throat 10 for a strip W of welting or other stock, and a reel 12 mounted on a shaft 14 for rotation alternately in opposite directions to cooperate with throat 10 to wind up the strip W in successive figure 8 convolutions.

The novel reel, indicated generally at 12, and which forms the subject-matter of the present application, consists of a support 14, carrying two L-shaped reel-arms 16, each having a cylindrical winding shank and said shanks being eccentrically mounted to turn about sleeves 18 formed on the support 14. Stems 20 on the arms 16 project downwardly through sleeves 18 and carry nuts 22 engaged by springs 24 to maintain the arms in position. Lugs 26 on the reel-arms seat in notches in the tops of sleeves 18 to prevent undesired turning of the arms. When an arm 16 is lifted against the resistance of spring 24 until its lug 26 clears the corresponding notch, the arm may be turned freely about sleeve 18 from the winding position shown in full lines in Fig. 2 to the releasing position shown in dotted lines, or vice versa. It is preferable, but not necessary to the success of the invention, that both arms of the reel be mounted for turning, as illustrated.

In order to clamp the end of a strip which

is to be wound into a hank, an abutment 30 on support 14 is provided to co-operate with the base of an arm 16 to jam or clamp the end of the strip therebetween, when the arm 5 is turned back from releasing to winding position.

According to the modification shown in Fig. 3, the abutment 30 is mounted for adjustment by a screw-and-slot mounting 32, 10 and the co-operating faces of the abutment and the base of arm 16 are beveled so that the strip W may, if desired, be clamped or released by vertical as well as rotary movement of arm 16.

15 While I have described my invention with relation to a machine for winding strips of welting or other stock, it is in various aspects capable of more general use, and it is not the intention to limit its scope thereby, 20 or otherwise than by the terms of the appended claims.

Having described my invention, what I claim as new and desire to secure by Letters Patent of the United States is:

25 1. A winding machine comprising, in combination, a rotary support having a plurality of arms extending parallel to its rotational axis, one of said arms being eccentrically swivelled upon the support, and connections 30 between the swivelled arm and the support constructed and arranged to permit the turning of said arm upon the support from a winding position into a releasing position in which the arm is displaced transversely 35 with relation to the support.

40 2. A winding machine comprising, in combination, a rotary support, an arm having a shank portion and a laterally extended end, and connections between the arm and support comprising a longitudinal extension of 45 said shank eccentrically swivelled in said support so that said shank will be located nearer the rotational axis of the support when said end is turned inwardly than when said end is turned outwardly.

45 3. A winding device comprising, in combination, a support, a stud mounted upon the support, an arm eccentrically swiveled upon the stud and having a laterally extended end, and means for yieldingly retaining the arm with the end extending outwardly in winding position.

50 4. A winding device comprising, in combination, a support, an arm swiveled eccentrically thereon, a clamping member secured

5 to the support in operative relation to the base of the arm, and means for yieldingly retaining the arm in position to clamp a strip of stock between the base of the arm and the clamping member and adapted to 60 permit rotation of the arm to move the base out of operative relation to the clamping member.

5. A reel comprising, in combination, a support, winding arms upon the support, 65 and a clamp member on the support, the arms being mounted on the support in such a manner that they may be moved to increase the effective diameter of the reel and simultaneously to cooperate with said member to 70 clamp the end of a strip of stock which is to be wound on the reel.

6. A reel comprising, in combination, a support, and members carried by said support to clamp the end of a strip of stock 75 and hold the strip wound thereon, said members being relatively movable to decrease the effective diameter of the reel to facilitate removal of the strip after winding and simultaneously to release the end of the 80 strip.

7. A reel comprising, in combination, a support, a fixed abutment, and an eccentrically-mounted reel-arm so constructed and arranged that turning of the arm on its axis 85 to increase the effective diameter of the reel will jam the end of a strip of stock between the abutment and the arm.

8. A reel comprising, in combination, a support, a plurality of reel-arms eccentrically swivelled thereon so that the effective diameter of the reel may be increased or diminished by turning the arms, and means for clamping the arms against turning. 95

9. A reel comprising, in combination, a support, and an L-shaped reel-arm pivotally mounted thereon so that the horn portion of the L may be turned outward for reeling a strip of stock or inward for removing the 100 strip after reeling, the pivotal mounting of the L-shaped arm being eccentric with respect to the axis thereof, so that turning the arm inward decreases the effective diameter of the reel to facilitate removal of a 105 strip reeled thereon.

In testimony whereof I have signed my name to this specification.

JAMES A. BROGAN.
